UNITED STATES PATENT OFFICE

DOROTHY BLANCHE MILLER, OF REPTON, ISLE OF WIGHT, ENGLAND

FUNNEL FOR LIQUIDS

Application filed December 26, 1929, Serial No. 416,569, and in Great Britain February 7, 1929.

This invention relates to improvements in filling funnels for liquids of the kind provided, inside the upper end of the outlet or neck of the funnel, with a float-actuated signal for giving an indication when the hot-water bottle, oil lamp or other receptacle with which it is used is full of liquid.

The present invention has more particular reference to funnel fitments of the above kind of the unshrouded type in which a signal and a float are connected, respectively, to the upper and lower ends of a wire which is guided within the neck of the funnel. Heretofore in this type of fitment the wire has been mounted so that it can move only vertically or axially in relation to the funnel, its movement being controlled either by mounting it in a long guide sleeve or else by providing an additional guide at the lower end of the float.

Now according to the present invention I provide a fitment adapted to be inserted in any shaped funnel for liquids and, in particular, in those funnels the necks of which are tapering, said fitment to be affixed in the funnel or inserted separately therein as a movable fitment for the purpose of indicating when receptacles for liquids are full, and consisting of a support or cross-bar bracket with a guide-hole therein for the passage of a thin rod or wire connecting an indicator, and a narrow float, the said support being so constructed that the in-poured liquid will impinge direct upon the said float and the diameter of the guide hole being large relatively to that of the rod or wire so that the said float will swing loose with the rod or wire to which it is attached within the neck of the funnel.

In one convenient construction the improved fitment may consist of a cross-bar bracket, a short narrow tube or wire with a guide-hole, a thin rod or wire, a small indicator in the nature of a little flag or ornament, and a narrow float. The said cross-bar bracket has in its centre a hole over which hole the short narrow tube or wire with a guide-hole is fixed to act as a guide to the finger and give a hole to the fitment and enable it to be slipped in and out of the funnel. The said rod or wire passes through

the short tube or wire with a guide-hole and through the hole in the said cross-bar bracket, the small indicator being at the upper end of the rod or wire and the narrow float being at the lower end of the rod or wire. 55 The said hole in the cross-bar bracket is sufficiently large to permit the thin rod or wire which passes through it to swing loose, thus enabling the narrow float attached to the lower end of the rod or wire to swing loose 60 too, whilst the said tube or wire with a guide-hole, being quite short and of the same diameter as the said hole in the centre of the cross-bar bracket, also permits of the loose-swinging of the rod or wire and float. By being narrow this short tube or wire with a guide-hole does not obstruct the liquid when it is poured into the funnel. The cross-bars of the said bracket are quite narrow and thin 65 to enable the in-poured liquid to impinge directly on the float and pass unimpeded into the funnel-neck and receptacle. One cross-bar of the bracket is bent in a downward direction at its extremities to enable the fitment to grip the inner sides of the upper end of the 70 narrow outlet or neck of the funnel from where it can be removed and replaced as desired, or in which it can be thus fixed permanently. When the said fitment is in position the small indicator rests on the top of 75 the short tube or wire with a guide-hole immediately above the funnel-neck or outlet. The said float by being narrow can be inserted in any shaped funnel for liquids and, in particular, in those funnels the necks of 80 which are tapered, the narrowness of the float also enables it to have freedom of action with the rod or wire to which it is attached when swinging loose within the neck of the funnel. The said indicator prevents the said 85 rod or wire from falling through the short tube or wire with a guide-hole in the said cross-bar bracket.

In the functioning of the fitment the funnel is placed in the opening in the receptacle 90 and the liquid is poured into the funnel. This liquid impinges on the float and, pushing it down, automatically adjusts it. To ascertain when the receptacle is full an occasional pause in the pouring-in of the liquid 100

is made when, if the liquid has risen sufficiently high in the receptacle to begin to enter the funnel-neck, the float rises and slightly pushes up the small indicator. When the liquid has penetrated sufficiently into the funnel-neck from the inside of the receptacle and a further pause in the pouring-in of the liquid is made, the float again rises and, by reason of its buoyancy and the fact that it is loose-swinging, shoots or bobs up and strikes the cross-bar bracket, which final rise of the float and indicator signifies that the receptacle is full.

The present invention is more particularly described with reference to the accompanying drawings, in which:—

Figure 1 is a perspective view of the cross-bar bracket portion of the fitment; and

Figure 2 is a sectional side elevation showing the fitment applied to a funnel inserted in the neck of a hot-water bottle.

As shown, the reference letter A indicates the funnel and F a hot-water bottle. The cross-bar bracket D (Figure 1) has in its centre a hole C over which is affixed the short narrow tube T. The reference letter H indicates the thin rod or wire, whilst B indicates the indicator which, when in its lowest position, rests on the top of the tube T just above the outlet or neck of the funnel. E indicates the narrow float.

The float E, being narrow and swinging loose, does not interfere with the pouring-in of the liquid, but the funnel outlet could, if desired, be expanded to expedite the filling of the receptacle.

What I claim is:—

1. An attachment for funnels comprising a bracket to fit in the funnel at the upper end of the neck thereof, said bracket providing large open spaces for the flow of a liquid and provided at its center with a guide opening and a short tube around said opening, a float, an indicator, and a stem passing loosely through the central guide opening in the bracket whereby it may rock in said opening, the float being secured to the lower end of the stem to be housed in the neck of the funnel and rock freely therein, and the indicator being secured on the upper end of the stem above the bracket.

2. An attachment for funnels comprising a bracket to fit in the funnel at the upper end of the neck thereof and consisting of wires disposed in angular relation, the outer ends of some of the wires being turned downwardly and a guide ring connecting the inner ends of the wires, a stem passing loosely through the guide ring, an indicator on the upper end of the stem of greater diameter than the guide ring adapted at times to rest on the guide ring, and a float depending from the lower end of the stem to be housed in the neck of the funnel, the diameter of the float being appreciably less than the diameter of the neck whereby it may rock freely in the neck and greater than the diameter of the guide ring whereby it may abut the under side of the ring.

In witness whereof I have hereunto signed my name.

DOROTHY BLANCHE MILLER.
